UNITED STATES PATENT OFFICE.

RICHARD SMITH, OF PHILADELPHIA, PENNSYLVANIA, ASSIGNOR TO
MACKELLAR, SMITHS & JORDAN, OF SAME PLACE.

DESIGN FOR PRINTING-TYPES.

Specification forming part of Design No. 7,154, dated February 3, 1874; application filed January 8, 1874.
[Term of Patent 7 years.]

To all whom it may concern:

Be it known that I, RICHARD SMITH, (assignor to MACKELLAR, SMITHS & JORDAN,) of the city and county of Philadelphia, Pennsylvania, have invented and produced a new and original Design for Printing-Type, of which the following is a specification:

The nature of my design is fully shown in the accompanying typographic impression, to which reference is made.

Having set forth my invention, what I claim as new is—
The design for printing-type, as shown.

RICHARD SMITH.

In presence of—

GEO. WM. WITHAM,
W. HUNTSMAN.
